UNITED STATES PATENT OFFICE.

CHRISTOPHER GABRIEL EDEN, OF MANCHESTER, ENGLAND, ASSIGNEE TO HANS
RENOLD LIMITED, OF MANCHESTER, ENGLAND.

DRIVING-CHAIN OF THE SILENT TYPE.

1,180,577.

Specification of Letters Patent. Patented Apr. 25, 1916.

Application filed June 20, 1914. Serial No. 846,282.

To all whom it may concern:

Be it known that I, CHRISTOPHER GABRIEL EDEN, a subject of the King of Great Britain, and resident of Progress Works, 5 Brook street, Manchester, England, have invented certain new and useful Improvements in Driving-Chains of the Silent Type, of which the following is a specification.

This invention relates to chains of the 10 type usually called silent chains, made from stamped, or pressed links or coined links, that is to say, links shaped from blanks by dies in an analogous manner to that in which coins are made, wherein the gearing 15 faces of the teeth are formed by bending the ends of the links at right angles to the webs, and the links are connected together by bushes and studs.

It is the principal object of the invention 20 to provide a chain of simple construction with links of high tensile strength, and bearings for the studs of the full available width across the chain.

Another object is to provide a chain 25 which, while fulfilling these requirements, will gear on both faces if needed.

Further objects are to provide a cheap 30 construction in which heat treatment of the body of the link is obviated, while the chain is kept light, thus minimizing wear and noise.

The invention is illustrated in the accompanying drawings in several examples of construction.

35 In the drawings:—Figure 1 is a plan view, partly in section, of a chain with “rectangular” inner combinations, suitable for gearing on both faces with circumferentially grooved chain wheels; Fig. 2 is a side elevation, and Fig. 3 is an end elevation of the same chain. Fig. 4 is a plan view, 40 partly in section, of a chain with I-shaped inner combinations, suitable for gearing on both faces with circumferentially grooved chain wheels; Fig. 5 is a side elevation, and Fig. 6 is an end elevation of the same chain. Figs. 7, 9 and 11 are plan views of one joint 45 of modified constructions of chains with “rectangular” inner combinations. Figs. 8, 50 10 and 12 are plan views of one joint of modified constructions of chains with I-shaped inner combinations. Fig. 13 is a side elevation of a half-I link for a chain suitable for gearing on both faces with cir-

cumferentially grooved chain wheels. Fig. 55 14 is a side elevation of a half-I link for a chain suitable for gearing on one face only with circumferentially grooved chain wheels. Fig. 15 is a side elevation of a half-I link for a chain suitable for gearing on one face 60 only with a simple chain wheel without circumferential grooves.

In the drawings, A A are the half-I or channel section links of the inner combination, which are held together by the bushes 65 B B on to which they are forced until they touch, as shown at T, either with their end-projections P P pointing toward one another, as in Fig. 1, or away from one another as in Fig. 4. The bushes extend outward 70 beyond the link side-faces on both sides of the inner combination, as shown at B B. These elements are connected to form a chain by outer combinations consisting of 75 half-I links C C, placed one on each side of the inner combinations with their end-projections Q Q pointing inward as shown, and by the studs D D, which may be riveted to the connecting links as shown at R. It is of great importance that the studs D D 80 should be firmly held where they are riveted.

Either the edges of the end-projections Q Q are suitably formed to work against the side-faces of the adjacent links as shown at W, Fig. 1, or the edges of the bushes B B 85 are so formed as shown at V, or both the edges of the end-projections Q Q and of the bushes B B are so formed, wherever relative motion of the edges and the side-faces can take place.

90 It will be seen that practically the full width of the chain is available for providing bearing surface for the studs. The gearing faces are formed on the end-projections of the links as shown at G.

95 In some chains it may be convenient or desirable to have the bushes in contact with the end-projections P P and Q Q, as shown in Figs. 7 and 8; the bushes and the end-projections P P of the inner combinations 100 will then mutually support one another, and the surfaces of the end-projections Q Q of the outer combinations can be suitably treated to render them fit to work against the outside of the bushes. This construction has the advantage also of making the 105 chain more rigid to resist lateral whipping. Other modified constructions having the

same advantages are shown in Figs. 9, 10, 11 and 12. In the chains shown in Figs. 9 and 10 the end-projections of the links of the inner combinations are bent at right angles to the gearing faces, as shown at X, and their edges are in contact with the bush at each end of the inner combination; whereas in the chains shown in Figs. 11 and 12 the end-projections of the links of the outer combinations, as shown at Y, as well as the end-projections of those of the inner combinations, as shown at X, are bent at right angles to the gearing faces, and their edges are in contact with the bush at each 15 end of the inner combinations.

The links used in any of these constructions may have webs of the full depth of the chain as shown in Fig. 8, or of less than the full depth as shown in Fig. 7, and in 20 the latter case the circumferential grooves on the chain wheels need extend only part of the way down the radial depth of the teeth. Again, the webs may be formed with a space to clear the tooth intermediate 25 between those engaged with or adjacent to the gearing faces of the link, as shown in Fig. 15, so that a simple chain wheel may be used without circumferential grooves at all. Further, the links may have gearing 30 faces on both sides as shown in Fig. 13, or on one side only as shown in Figs. 14 and 15.

Chains made in accordance with this invention are light and durable, cheap to manufacture, and easy to assemble, to take 35 apart and to join up; and they are readily made suitable to gear on one face only, or on both faces, with simple or circumferentially grooved chain wheels.

Having thus described my invention, what 40 I claim as new and desire to secure by Letters Patent is:—

1. The combination in a chain of a pair of inner links of half-I section with corresponding openings therein near to one end 45 of each, a cylindrical bush fitting in the corresponding openings of said links, and projecting outwardly beyond the link webs, said links being formed with laterally projecting ends constituting gearing faces, a 50 pair of outer links also formed with laterally projecting ends constituting gearing faces, the links of said outer pair being situated with their ends one at either side of the inner links at one end thereof, and a 55 stud secured to said outer links, and connecting them together, and passing through the cylindrical bush of the inner pair of links.

2. The combination in a chain of a pair 60 of inner links of half-I section formed with laterally projecting ends constituting gearing faces, said projecting ends being directed toward one another and contacting at their inner faces, said links having also 65 openings near the ends thereof, a cylindri-

cal bush passing through and fitting in the corresponding openings at one end of each link, and projecting beyond the link-webs, a pair of outer links formed with laterally projecting ends constituting gearing faces, 70 said links being situated with their ends one at either side of the inner links and with their projections inwardly directed, and a stud secured to said outer links, and connecting them together, and passing through 75 the cylindrical bush of the inner pair of links.

3. The combination in a chain of a pair of inner links of half-I section formed with openings therein near their ends, a cylindrical bush fitting in corresponding openings of said links and projecting beyond the same outside the link webs, said links having laterally projecting ends bent over at their inner ends to abut against the bush, 80 said laterally projecting ends also constituting the gearing faces for the links, a pair of outer links formed with laterally projecting ends constituting gearing faces, 85 said links being situated with their ends one at either side of the inner links and with their projections inwardly directed, and a stud secured to said outer links, and connecting them together, and passing through 90 the cylindrical bush of the inner pair of links.

4. The combination in a chain of a pair of inner links of half-I section formed with openings therein near their ends, a cylindrical bush fitting in corresponding openings of said links and projecting beyond the same outside the link webs, said links having laterally projecting ends bent over at their inner ends to abut against the bush, 100 said laterally projecting ends also constituting the gearing faces for the links, a pair of outer links formed with laterally projecting ends constituting gearing faces, 105 said links being situated with their ends one at either side of the inner links and with their projections inwardly directed, said projections being also bent over to bear against the bush, and a stud secured to said outer links, and connecting them together, and passing through 110 the cylindrical bush of the inner pair of links.

5. The combination in a chain of a pair of inner links of half-I section formed with openings therein near their ends, a cylindrical bush fitting in corresponding openings of said links and projecting beyond the same outside the link webs, said links having laterally projecting ends directed inwardly toward one another, and bent over 115 at their inner ends to abut against the bush, 120 said laterally projecting ends also constituting the gearing faces for the links, a pair of outer links formed with laterally projecting ends constituting gearing faces, 125 said links being situated with their ends one at either side of the inner links and with their projections inwardly directed, and a stud secured to said outer links, and connecting them together, and passing through 130 the cylindrical bush of the inner pair of links.

one at either side of the inner links and with their projections inwardly directed, and a stud secured to said outer links, and connecting them together, and passing 5 through the cylindrical bush of the inner pair of links.

In witness whereof, I have hereunto signed

my name this 2nd day of April, 1914, in the presence of two subscribing witnesses.

CHRISTOPHER GABRIEL EDEN.
